CLAIM

The ornamental design for a blended turn button set, as shown and described.

DESCRIPTION

FIG. 1 is a perspective view of a blended turn button set in an unlatched position;

FIG. 2 is a perspective view of the blended turn button set of FIG. 1 in a latched position;

FIG. 3 is a top plan view of the blended turn button set of FIG. 1 in the unlatched position;

FIG. 4 is a front elevation view of the blended turn button set of FIG. 1 in the unlatched position;

FIG. 5 is a left side elevation view of the blended turn button set of FIG. 1 in the unlatched position;

FIG. 6 is a rear elevation view of the blended turn button set of FIG. 1 in the unlatched position;

FIG. 7 is a right side elevation view of the blended turn button set of FIG. 1 in the unlatched position; and,

FIG. 8 is a bottom plan view of the blended turn button set of FIG. 1 in the unlatched position.

The broken lines shown represent environmental structure and form no part of the claimed design.
